GOLFER'S BRUSH

Donald J. Protsman, 2815 E. 95th St., Chicago, Ill.

Filed Dec. 20, 1962, Ser. No. 72,908

Term of patent 7 years

(Cl. D9—2)

FIG. 1 is a front elevation view of one side of the golfer's brush which is the subject of this invention showing my new design.

FIG. 2 is a side elevation view of the golfer's brush of the present invention.

FIG. 3 is a top view of the golfer's brush shown in FIG. 1 showing the ornamental design from that direction.

FIG. 4 is a bottom view of the golfer's brush shown in FIG. 1.

FIG. 5 is a front elevation view of the reverse side of the golfer's brush shown in FIG. 1.

I claim:
The ornamental design for a golfer's brush, as shown.
